(57) **CLAIM**

I claim an ornamental design for the bicycle light housing, as shown and described.

DESCRIPTION

FIG. 1 is an upper front perspective view of the bicycle light housing;

FIG. 2 is a lower bottom perspective view of the bicycle light housing;

FIG. 3 is a rear lower side perspective view of the bicycle light housing;

FIG. 4 is a front elevational view of the bicycle light housing;

FIG. 5 is a rear elevational view of the bicycle light housing;

FIG. 6 is right side view of the bicycle light housing;

FIG. 7 is a left side view of the bicycle light housing;

FIG. 8 is a top plan view of the bicycle light housing of FIG. 1; and,

FIG. 9 is a bottom plan view of the bicycle light housing of FIG. 1.

The broken-line disclosures illustrate portions of the bicycle light housing in which the design is embodied that form no part of the claimed design.
